UNITED STATES PATENT OFFICE

JARL PEARSON, OF ONTARIO, CALIFORNIA, ASSIGNOR OF ONE-HALF TO HUBERT F. LUCAS, OF ONTARIO, CALIFORNIA

CAN FILLING MACHINE

Application filed August 13, 1929. Serial No. 385,607.

This invention relates to mechanism for automatically filling cans or like containers with fruit or other commodities, and the general object of the invention is to provide a relatively simple, positively operated mechanism whereby fruit or other commodities may be measured and discharged into a can and pressed into the can before the can is sealed.

A further object is to provide mechanism of this character which includes a hopper for containing the commodity, a vertically movable measuring cup operating vertically through the hopper, and means for over-tipping the measuring cup so as to discharge it into a spout whereby it is immediately discharged into a can.

Another object is to provide means whereby the capacity of the measuring cup may be regulated.

Still another object is to provide means for returning the measuring cup to its vertical position after it has been tipped to discharge its contents, said means being operated automatically.

A further object is to provide a tilting mechanism which includes a hopper and a column supporting the measuring cup which is movable vertically through the hopper so that it will not crush or damage the fruit contained within the hopper.

Other objects will appear in the course of the following description.

My invention is illustrated in the accompanying drawings, wherein:—

Figure 1 is a fragmentary side elevation partly in section of a can filler constructed in accordance with my invention;

Figure 2 is a front elevation partly in section;

Figure 3 is a vertical sectional view on the line 3—3 of Figure 2;

Figure 4 is a top plan view of the structure shown in Figures 1, 2 and 3;

Figure 5 is an enlarged sectional view through the cup showing in dotted lines the cup tipped;

Figure 6 is a top plan view of the cup and a portion of the wall between the main hopper and the auxiliary hopper.

Figure 7 is a detailed elevation of the lifter operating lever and its cam.

Figure 8 is a fragmentary section of the hopper showing in elevation the modified means for tilting the cup to its discharge position.

In Figures 1 to 5, I have illustrated a measuring device and can filler, though it is to be understood that this device may be used for filling bags, sacks or any containers, or merely for the purpose of measuring fruit and discharging it into a spout, permitting the fruit to be afterwards treated.

In these drawings, 10 designates a hopper of any suitable character, in which the fruit is placed, which hopper may be of any desired size. Disposed below the hopper is a guide 11 through which slides the preferably cylindrical column 12 or lifter bar. At one side of the hopper 10, there is disposed a chamber 13 or discharge hopper. Mounted upon the upper end of the column or lifter bar is a measuring cup 14. This measuring cup is provided with the shank 15 extending downward from its bottom, this shank being pivoted at 16 upon the column or lifter bar. The shank 15, as will be seen from Figure 5, is off-set with relation to the cup so that when the cup is turned into a vertical position, it is disposed entirely above and in alignment with the lifter bar or vertical slideable column. The cup is open at the top, closed at the sides, and contains a definite quantity of material. Preferably the cup has certain details of construction which will be hereafter stated.

The lifter bar 12 at its lower end is connected by an adjustable link 17 to a lever 18 pivoted at 19 to a bracket 20. The opposite end of this lever is pivoted to a sleeve 18a and has screw-threaded engagement with the shank of the link 17, this link 17 having a member 17a pivoted to the lower end of the column 12. This lever is actuated by a roller 21 mounted on a disk 22 carried on a shaft 23. This shaft has upon it the gear wheel 24 which is engaged by a pinion 25 mounted upon a shaft 26, this shaft carrying upon it the driving pulley 27.

Thus, by the rotation of the shaft 23 and

of the disk 22, the lever 18 is given an oscillating movement in a vertical plane. The link 17 is adjustable within the sleeve 18a so as to raise or lower the vertically sliding column or lifter bar 12.

It will be seen that with this mechanism, the cup 14 is given a vertical movement upward through the hopper. The cup, after it has been lifted up, is tilted, then returned and then carried downward again into the hopper 10, where it becomes filled with the fruit or vegetables and the cup is again lifted, and so on. Each time the cup is lifted, it is tilted to discharge the contents of the cup, and for this purpose, as shown in Figure 2, I have provided a shaft 27 mounted on bracket 27a, the shaft having a downwardly projecting finger 29 and an arm 29a. The extremity of the finger 29 carries upon it a rubber roller 28 and the arm 29a is connected by a link 30 to a lever 31 by an adjustable clevis 39 held in adjusted position by a nut 39a. This lever is pivoted at one of its ends, as at 32, to a bracket and is operated by means of a cam 33.

When the cup has been raised fully out of the hopper, the cam 33 operates to permit downward movement of the link 30, thus swinging the finger 29 to cause the ball or roller 28 to tilt the cup upon its pivot 16 to cause the cup to move from a vertical position to a discharge position. The cup swings over into the chamber or hopper 13 which is formed with a downwardly extending spout 34 beneath which the can A is disposed.

For the purpose of returning the cup to its vertical position, I provide a crank arm 35 carried on a shaft 35a, the shaft being mounted in bearings 36. This arm 35 carries a rubber roller 37, the arm being capable of being raised from the position shown in Figure 3 to the position shown in Figure 1 or lowered again to the position shown in Figure 3. The shaft 35a is connected by links 37 and 38 to a lever 40 pivoted at 41 upon a supporting bracket and engaged by a cam 42 mounted upon the shaft 43. When the cup is tilted by the finger 29, it will be received upon the rubber roller 37 which will be in the position shown in Figure 3 and when the fruit has been discharged from the cup into the hopper 13, the cam 42 will elevate the lever 40 and, lifting the arm 35, return the measuring cup 14 to its initial position, the lever 40 being again lowered to lower the arm 35. When the cup 14 has been returned to its original position upon the column 12, the column then moves downward to the bottom of the hopper and the cup is again filled.

The can A is preferably carried upon an intermittently movable conveyor, for instance, a belt 43 and after the fruit has been discharged into the can, the belt moves one

step to bring the new can beneath the spout 34.

The cam 33 is mounted upon a shaft 44 which carries upon it the gear wheel 45. The gear wheel 24 is mounted upon the shaft 23. These gear wheels are both driven by any means, as for instance by a counter shaft and pinions (not shown).

It will be seen that with this construction, as soon as the measuring cup has been lifted above the hopper 10, the finger 29 is operated to tip the cup over from its vertical position to its discharge position, this cup being received upon the rubber roller 37 carried by the crank 35, the crank 35 being intermittently operated by means of the cam 42 so that when the contents of the cup have been discharged, the cup is returned to its vertical position and the supporting column or lifting bar 12 immediately moves downward, carrying the cup again into the hopper.

While I have illustrated in Figure 3 a bell crank mechanism for tilting the can from its vertical position to its discharge position, I do not wish to be limited to this, as I may use means such as shown in Figure 7, where a bracket 48 is mounted upon the hopper and extends above the path of movement of the measuring cup 14, this bracket having adjustably mounted thereon a downwardly and laterally inclined arm or lifter 49, illustrated as having a horizontal portion which is slotted at 50 for engagement with the bracket and is held in adjusted position by the wing nut 51. By this means, when the cup rises, the cup will strike this inclined member 49 and will then be tilted from its vertical position to its discharge position. The cup is to be returned to its vertical position by the means heretofore described.

The cup is preferably constructed as illustrated in Figure 5, having an adjustable false bottom 52. This is mounted upon an adjustment stud 53 which extends down through the stationary bottom 54 of the cup and is provided with the knurled adjustment nut 55. This will permit a downward movement of the false bottom 52 but will prevent an upward movement of the false bottom beyond a predetermined point regulated by the nut.

Extending upward from the stationary bottom 54 are the studs 56 carrying the coiled compression springs 57 which bear against the bottom of the cup. This permits the bottom of the cup to yield slightly under weight until the false bottom 52 moves downward against the studs 56. The extent to which the false bottom 52 may be raised under the action of the spring 57 depends upon the regulation of the nut 55.

The stationary bottom 54 is provided with drainage openings 59 so that the juices may drain off through these drainage openings as the cup moves from the hopper.

Preferably the can filling mechanism will be mounted upon a supporting frame 60 having legs and provided with suitable bearings for the shafts 26 and 44 and apertures for the passage of the rods 30 and 38. The guide 11 is integral with a cylindrical column section or support 61 attached to the top of the frame 60 and having a top wall 62 to which the base 63 of the hopper 10 is attached, the cylindrical guide 11 being disposed, of course, immediately beneath the opening of the hopper.

Preferably, and as illustrated, the lower end of the column will be supported upon a knuckle 17a which carries the screw-threaded stem 17 which is engaged by the screw-threaded end of member 18a which is pivoted to the extremity of the lever 18. Thus by removing the pivot bolts of either one of these parts 17a or 18a, it is possible to adjust the column 12 vertically to secure exactly the proper stroke for the column. It will be seen that the cup 14 has its shank 15 disposed to one side of the middle so that this cup, when turned over, will be disposed directly in alignment with the column 12 so that a slight impetus will act to tilt the cup from its vertical position to its discharge position.

The operation of this mechanism will be obvious from what has gone before. Assuming that the hopper is filled with fruit, then as the lifter 12 rises, the cup, which has heretofore been disposed below the bottom of the hopper, rises through the hopper so that the cup is filled, and when the cup reaches its most elevated position, the cup is tilted by means of the oscillating rubber-covered roller 28 to its discharge position, that is, the dotted position shown in Figure 5. As it is tilted, it is received upon the rubber-covered roller 37, this roller being in a lowered position when the cup has discharged its contents. The crank arm 35 now swings upward, returning the cup to its initial position, and then the column lowers, carrying the cup downward into and through the hopper and into the guide 11 in order to refill the cup. As the cup turns over, it discharges into the hopper or chamber 18 and out through the spout 34. It will be seen that I have provided at the lower ends of the rods 30 and 38 an adjustable connection with the corresponding levers 18 and 40 comprising a bifurcated link 39 for each of these rods through which the rods pass and have screw-threaded engagement, the links being held in adjusted position on each rod by means of the nut 39a. Provision is thus made for the adjustment of either of the rods 30 or 38 so as to adjust the throw of the cranks supporting the rubber rollers 28 and 37. Provision is also made through adjustable clevis 18a for adjusting the column 12 vertically.

This mechanism may be used for filling any size can, it being simply necessary to regulate the size of the measuring cup or to provide in some cases that the measuring cup shall operate twice or more times to any movement of the belt 43 which carries the cam A. This machine will handle any fruit or vegetable to be canned unless the articles must be placed in the can in a certain definite position, such as canned asparagus. The speed can be regulated to fill as many as thirty cans a minute, doing away with as many as twenty to eighty packers, according to the size of the cup used.

While I have illustrated certain details of construction and arrangement of parts which I believe to be particularly effective, I do not wish to be limited to the exact details or the exact arrangement, as it is obvious that many changes might be made without departing from the spirit of the invention as defined in the appended claims.

I claim:

1. A filling machine of the character described including a hopper, a lifter movable upward through the hopper, a measuring cup open only at its upper end pivotally connected to the upper end of the lifter and movable therewith through the hopper the cup normally resting upon the upper end of the lifter, means for reciprocating the lifter, means exterior to the lifter and disposed above the hopper for tilting the measuring cup to discharge its contents when the lifter has reached its fully elevated position, and means exterior to the lifter for returning the measuring cup to an upright position on the top of the lifter when the contents of the measuring cup has been discharged.

2. A filling machine of the character described, comprising a hopper, a lifter movable vertically through the hopper, a cup having a shank pivoted to the lifter, the measuring cup being movable with the lifter upward through the hopper, a spout, means exterior to the lifter and extending over the top of the hopper for tilting the cup when the lifter has reached its highest position to thus discharge the contents of the cup into the spout, and means exterior to the lifter then acting to return the measuring cup to its initial position prior to the descent of the lifter.

3. A filling machine of the character described, comprising a hopper, a lifter movable vertically through the hopper, means for reciprocating the lifter, a measuring cup normally resting upon the upper end of the lifter, oscillating means mounted opposite the position of the cup when at its highest point and acting to tilt the cup from its vertical receiving position to a tilted discharge position, a spout into which the cup discharges, and oscillating means adapted to receive the cup as it is tilted and then lift

it back to its initial position, and means for oscillating said tilting means and the cup returning means.

4. A filling machine of the character described, comprising a hopper, a lifter movable vertically through the hopper, a measuring cup having a flat bottom resting upon the upper end of the lifter, the cup having an offset shank pivoted to the lifter, an oscillating member mounted opposite to the uppermost position of the measuring cup and when oscillated acting to tilt the measuring cup to a discharge position, a spout into which the measuring cup discharges, and an oscillating member acting to return the cup to its initial position after it has discharged its contents, and means operating the lifter, oscillating tilting means and the cup returning means comprising a driven shaft, and cams mounted upon the driven shaft and by which said several instrumentalities are operatively engaged.

5. A filling machine of the character described, comprising a hopper, a lifter movable vertically through the hopper, a measuring cup having a flat bottom resting upon the upper end of the lifter, the cup having an offset shank pivoted to the lifter, an oscillating member mounted opposite to the uppermost position of the measuring cup, and when oscillated acting to tilt the measuring cup to a discharge position, a spout into which the measuring cup discharges, an oscillating member acting to return the cup to its initial position after it has discharged, means operating the lifter, the oscillating tilting means and the cup returning means comprising a driven shaft, cams mounted upon the driven shaft, and levers operatively connected to said several instrumentalities and operated by said cams.

6. A filling machine including a hopper, a lifter movable vertically through the hopper, a measuring cup adapted to rest flat against the upper end of the lifter and having an offset shank pivoted to the lifter, an oscillatable member disposed immediately opposite the uppermost position of the cup and adapted when oscillated to tilt the cup upon its pivot to discharge the contents thereof, a spout into which the measuring cup discharges, means for returning the measuring cup to its initial position, comprising a lever having a roller at one end bearing against the measuring cup, a link depending from said lever, a vertically disposed link for operating the tilting means and an adjustable link connected to the lower end of the lifter, levers to which the several links are respectively connected, cams operating on the several levers, and means for driving said cams.

7. A filling machine including a supporting frame, a hopper, a tubular guide mounted upon the supporting frame and supporting the hopper, a column movable upward

through the tubular guide and through the hopper and having a vertical slot at its upper end, a measuring cup having an off-set shank disposed within said slot and pivoted to the walls thereof, the cup normally resting vertically upon the upper end of the column, means for intermittently lifting the column upward through the guide and hopper, means exterior to the column and cup acting when the cup has been entirely lifted to tilt the cup to discharge its contents over one wall of the hopper, means exterior to the column and cup acting to return said cup to its vertical position after it has been tilted, and means for actuating the column, the tilting means and the cup-returning means comprising a shaft, and cams mounted upon the shaft and engageable with said several means.

8. In a filling machine of the character described, a hopper, an article lifter, vertically movable through the hopper, a cup pivoted to the top of the lifter for tipping movement, and means outward of and extraneous to the lifter and disposed at the upper end of the path of movement of the lifter for causing said cup to tilt beyond its center and drop by gravity after the measuring cup has been lifted to a predetermined height.

9. In a filling machine of the character described, a hopper, an article lifter, vertically movable through the hopper, a measuring cup pivoted to the top of the lifter for tipping movement, and means outward of and extraneous to the lifter for causing said cup to tilt beyond its center and drop by gravity after the measuring cup has been lifted to a predetermined height, and cushioning means limiting the downward swing of the measuring cup and means acting automatically to return the cup to its initial position, including a roller against which the cup strikes when it descends and means for elevating said roller to lift the cup to a vertical position, said means after the cup has been tilted to a discharge position operating automatically.

10. In a filling machine of the character described, a hopper, an article lifting member movable vertically through the hopper and against one wall thereof, a cup hingedly mounted upon the upper end of the lifter for swinging movement downward and outward into a position discharging over said wall, a spout into which the cup discharges, means acting automatically to tilt the cup to a discharge position after the lifter has moved upward to a predetermined position, said means being extraneous to the lifter and disposed outward thereof, and means mounted upon the wall of the hopper exteriorly thereof to receive the cup when it is tilted to a discharge position and return the cup to a vertical position upon the top of the lifter.

11. In a filling machine of the character

described, a hopper, a member movable vertically through the hopper adjacent one wall of the hopper, a cup pivotally mounted upon the upper end of the member, a spout, means for tilting the cup to a discharge position and discharging the article carried by the cup into the spout after the cup has been lifted above the hopper including a pivoted arm disposed above the hopper and engaging the side of the cup when the cup has been fully lifted, and means for automatically swinging the arm in a direction to tilt the cup over to discharge its contents into the spout, and means then acting to return the cup to its initial position.

12. In a filling machine of the character described, a hopper, an article lifter, vertically movable through the hopper a cup pivoted to the top of the lifter for tilting movement, means outward of and extraneous to the lifter for causing said cup to tilt beyond its center and drop by gravity to a discharge position after the cup has been lifted to a predetermined height, and means separate from the tilting means and disposed exteriorly of the lifting means acting automatically to return the cup to its initial position.

In testimony whereof I hereunto affix my signature.
